CONTROL DEVICE

Robert K. Winning, Wauwatosa, Wis., assignor
to Clum Manufacturing Company, Milwaukee,
Wis., a corporation of Wisconsin

Application February 17, 1932, Serial No. 593,675

12 Claims. (Cl. 74—502)

This invention relates to improvements in control devices. It has particular application to the type of push and pull control rod which is commonly mounted on the dash of a motor vehicle 5 for control of engine parts or other parts having to do with the functioning of the vehicle.

It is the primary object of the invention to provide a novel, inexpensive and simple means for locking a control rod in a predetermined position or positions subject to immediate release by manipulation of a push button threaded in the knob of the control rod. It is my purpose to provide an organization in which a single release button may be employed for the actuation of 15 a detent mechanism effective in each of a plurality of positions of the rod. Other objectives of the invention will appear in the following disclosure thereof.

In the drawing:

20 Figure 1 is a view in axial section, of a device embodying the invention.

Figure 2 is a fragmentary sectional detail in the same plane illustrating the parts in different positions from those illustrated in Figure 1.

25 Figure 3 is a view in transverse section in the plane indicated at 3—3 in Figure 1.

Like parts are identified by the same reference characters throughout the several views.

A support typical of the usual instrument panel 30 is illustrated at 4 and is provided with an aperture through which extends the threaded plug 5 upon the reduced extremity of which disk 6 is held by upsetting the material of the plug as shown at 7. The disk 6 constitutes a head for the plug 35 which is held in clamping engagement with dash 4 by means of nut 8 and an interposed washer 9. The device is exteriorly finished by means of a stamped shell 10, apertured in registry with the tubular bore through plug 5 and having its marginal portions 11 formed about the margin of the head or disk 6.

The plug 5 serves as a mounting for a tubular barrel 12 upon which the inner end portion 13 of the plug is sleeved and compressed to retain 45 the parts in assembly. At the end of barrel 12 remote from the plug I provide a tubular anchorage fitting 15 into which are secured the inner and outer plies 16 and 17 of a flexible sheath through which the composite Bowden wire elements 18 and 19 are reciprocable. The inner element 19 preferably constitutes a stranded cable upon which a helical sheath is wound to maintain the strands in predetermined relation and to provide a smooth surface radially reciprocable 50 within the inner ply 16 of the flexible sheath. The

Bowden wire elements 18 and 19 are engaged together at their free end by a clamp tube 20 which has portions 21 deformed into clamping engagement with the Bowden wire elements, and also held by correspondingly deformed portions 22 5 of the tubular control rod 25.

The said control rod 25 is reciprocable within the barrel 12 and projects from the barrel through the bore of plug 5 and the registering aperture of the finishing plate or shell 10. To its outer end is 10 fixed a knob 26 whereby the control rod and the Bowden wire elements to which it is connected may be reciprocated.

Detent means are used for fixing one or more predetermined positions of the control rod and its 15 associated parts. A radial bore 27 in the disk 6 receives a compression spring 28 acting on a ball detent 29 in a direction tending to maintain the ball in either of the apertures 30 or 31 in the tubular control rod 25. When the ball registers 20 with one of these apertures and engages itself therein under the compression of spring 28, it locks the control rod against reciprocation until such time that the ball is forced sufficiently from the aperture 30 or 31 to enable the movement of 25 the control rod to thrust the ball entirely aside.

To release the ball detent I provide at 35 a release pin extending axially within the tubular control rod and normally held in a retracted position by a compression spring 36 acting upon the 30 push button 37 which is attached to the end of this pin. A tongue 38 pressed inwardly from the control rod serves as a stop to engage shoulder 39 and thereby to limit the outward movement 35 of the release pin with respect to the rod. This shoulder is formed by one of two peripheral 40 grooves 40 encircling rod 35 and having beveled margins at 41. These grooves register with openings 30 and 31 respectively, and the depth of the groove determines the extent to which the ball 40 is permitted to enter the apertures in the control rod.

When the push button 37 is pressed inwardly by the operator against the compression of spring 36, the beveled surfaces 41 move across 45 apertures 30 and 31 and act as cams to thrust out of holes 30 and 31 a detent ball engaged with either thereof. The diameter of the ball is sufficiently great so that when it is expelled from the aperture to the degree made possible 50 by the beveled cam surfaces 41, the center line of the ball will then be sufficiently above the control rod so that the control rod itself will complete the expulsion of the detent and will pass there-beneath. Figure 2 shows how the release pin 35 55

lifts the detent ball 30 when the operator depresses button 37.

An extension of the radial bore 27 across the diameter of the disk 3 serves to receive a guide pin 45 which performs a dual function in that it locks or keys the disk to the plug 5 and has a reduced terminal portion 46 engaged in an elongated slot 47 in the control rod to permit the reciprocation of said rod non-rotatably with respect to its mounting. The pin 45 and spring 28 are both maintained in assembly with the disk 6 by means of the finishing plate 10.

It will be observed that any number of detent positions may be provided for this device by simply multiplying the number of apertures 30, 15 and 31, and providing the release pin 35 with a corresponding number of related surfaces 41.

I claim:

1. In a control rod assembly, the combination 20 with an apertured mounting and a ball detent positioned in the aperture thereof, of an apertured hollow control rod reciprocable within said mounting and with the walls of the aperture of which said ball detent is engageable upon the 25 registration of said aperture with that of the mounting, and means carried by said control rod for initially moving said ball detent from its rod engaging position, the wall of said rod being of a thickness suitable to move said ball from the 30 aperture after initial movement of said ball by said means upon movement of said rod, but to engage said ball and positively prevent movement of said rod before initial movement of said ball by said means.

2. A control rod assembly comprising the combination with an axially bored mounting member and a radially movable detent carried thereby, of a circumferentially apertured tubular control rod movable axially through said mounting, 40 the aperture thereof being registerable with said detent for engagement thereby, and a releasing pin reciprocable within said control rod and provided with a cam surface engageable with said detent for the partial expulsion thereof from 45 said aperture, the wall of said rod being of a thickness suitable to move the ball from the aperture when the ball has been partially expelled from the aperture and the rod is thereafter moved.

3. A control rod assembly comprising the combination with a mounting and a hollow control rod reciprocable with reference to said mounting and provided with detent apertures, of a detent mounted in said mounting and receivable in the 55 apertures in said rod in each of a plurality of positions of said rod, and a single detent releasing means reciprocable in said rod and effective in each of said rod positions to release the engagement, between said detent and said apertures, 60 the wall of said rod being of a thickness suitable to move the detent from an aperture when the detent has been partially disengaged from said aperture and the rod is thereafter moved.

4. A control rod assembly comprising the combination with a mounting and an apertured control rod reciprocable with reference to said mounting, detent means carried by said mounting and alternatively engageable in a plurality of predetermined positions of said control rod 70 with the apertures therein, and a single detent releasing means carried by said control rod and movable with respect thereto and provided with detent engaging cam surfaces effective in the course of such movement to force said detent 75 means from the rod restraining position in each

of the said positions of said rod, the margin of said apertures being adapted to move said detent therefrom when said rod is moved after release as aforesaid.

5. A control rod assembly comprising a mounting plug having a head provided with a radial bore, a spring pressed detent reciprocable in said bore, a tubular control rod reciprocable through said plug and provided with a detent aperture registerable with said radial bore and adapted to receive said detent, a releasing pin reciprocable within said rod and carried thereby, and cam means connected with said pin and engageable with said detent to force it from rod restraining engagement in said aperture, the wall of said rod 15 being of a thickness suitable to move the detent from the aperture when the detent has been partially disengaged from the aperture and the rod is thereafter moved.

6. A control rod mounting comprising a threaded plug, a disk carried thereby and provided with a diametrical bore through said disk and plug, a detent reciprocable in said bore, a compression spring acting on said detent, a key in the portion of said bore opposite said detent, and a finishing 25 shell applied to said disk and closing the ends of said bore about said spring and key.

7. A control rod mounting comprising a threaded plug, a disk carried thereby and provided with a diametrical bore through said disk and plug, 30 a detent reciprocable in said bore, a compression spring acting on said detent, a key in the portion of said bore opposite said detent, and a finishing shell applied to said disk and closing the ends of said bore about said spring and key. 35

8. In a control rod structure, the combination of a mounting having a detent receiving socket 40 therein, a control rod reciprocable in said mounting transversely to the detent socket and provided with detent receiving apertures disposed to register with the detent receiving socket in certain positions of said rod, a detent in the mounting 45 socket having a surface engageable with the walls of the control rod aperture, said detent being adapted in one position, to deeply engage in the control rod aperture to positively prevent movement of said control rod, and in another position to impositively engage in the control rod aperture to prevent accidental movement of said rod, and independently adjustable means for controlling the positioning of the detent in positive and impositive locking relation to said rod. 55

9. In a control rod structure, the combination of a mounting having a detent receiving socket therein, a control rod reciprocable in said mounting transversely to said detent socket and provided with a detent receiving aperture adapted 60 to register with said socket in one position of the rod, a detent in the mounting socket adapted to engage the walls of the control rod aperture, said detent, in one position, being adapted for positively engaging the walls of said aperture 65 to positively lock the same against movement in either direction, and also adapted in another position, for yieldingly engaging the walls of said rod aperture at less depth to impositively lock the rod against accidental movement, and 70 adjustable means for manually controlling the positive and impositive locking relations of the detent to the control rod.

10. A control device comprising in combination, an escutcheon adapted to be mounted on a 75

supporting surface, a two part control rod supported by said escutcheon and reciprocable therein as a unit; said parts being capable of limited relative movement, a tumbler carried by said escutcheon and adapted to cooperate with one of said parts of said control rod to lock said part against reciprocable movement when said parts are in normal relative position, means for urging said tumbler into cooperation with said part, 5 means associated with the other of said parts for releasing said tumbler upon relative movement between said parts, a control knob for actuating said control rod, and resilient means adapted normally to retain said parts in normal 10 position.

11. A control assembly comprising an escutcheon tube adapted to be supported on a planular surface, a control knob having an axial chamber, 20 a two part control element mounted in said escutcheon and reciprocable as a unit therein, said control element comprising a rod and a tubular member encompassing said rod, one of said parts being secured to said knob, the ends of said parts 25 being spaced apart, and means for maintaining said parts in such positional relation comprising-

ing a spring surrounding said rod and disposed within said chamber.

12. A control assembly comprising in combination, an escutcheon tube adapted to be supported on the dash panel of an automotive vehicle, a 5 control rod mounted in said escutcheon tube and being reciprocable with relation thereto, said control rod comprising a shaft having a reduced portion, and a sleeve encompassing said shaft and having an opening therein overlying said reduced portion, a control knob, means for operatively connecting said control rod and sleeve to said knob whereby said sleeve and said shaft may be reciprocated as a unit, a tumbler adapted to cooperate with said opening in said sleeve 10 and being adapted to rest therein and upon the reduced portion of said shaft, and means associated with said shaft for ejecting said tumbler from the opening in said sleeve, said sleeve and said shaft being capable of limited relative longitudinal movement when said tumbler cooperates with said opening, and resilient means for resisting said relative longitudinal movement and for returning said sleeve and shaft to normal 15 position with relation to each other. 20 25
